CLASP CONSTRUCTION

Eugen Prestinari, Summit, and John F. Sand,
Newark, N. J., assignors to Gemex Company,
Union, N. J., a corporation of New Jersey

Application April 25, 1946, Serial No. 664,818

3 Claims. (Cl. 24—241)

1

This invention relates to a bracelet connecting device and, more particularly, to a safety catch construction for use with such a device.

One of the objects of this invention is to provide a thoroughly practical, economical and efficient bracelet connecting device having a safety catch. Another object is to provide a device of the above character in which the possibility of accidental opening of the connecting device is reduced to an absolute minimum. Another object is to provide a device of the above character which may be operated with ease and without discomfort. Other objects will be in part obvious and in part pointed out hereinafter.

The invention accordingly consists in the features of construction, combinations of elements, and arrangements of parts as will be exemplified in the structure to be hereinafter described, and the scope of the application of which will be indicated in the following claims.

In the accompanying drawings, in which is shown one of the various possible embodiments of this invention,

Figure 1 is a perspective view of the connecting device as assembled on the opposite ends of the watch bracelet;

Figure 2 is an exploded perspective view of the cover member of the connecting device;

Figure 3 is a perspective view of the actuating lever of the connecting device;

Figure 4 is a perspective view of the locking part of the connecting device;

Figure 5 is a perspective view of the housing or channel-shaped portion of the connecting device;

Figure 6 is a longitudinal sectional view of the connecting device with the parts in the locked position;

Figure 7 is a longitudinal sectional view of the connecting device with the safety catch in a locked position and the cover in an unlocked or upper position;

Figure 8 is a longitudinal sectional view of the connecting device with the cover and safety catch in the unlocked position; and

Figure 9 is a transverse sectional view taken along the line 9—9 of Figure 6.

Similar reference characters refer to similar parts throughout the several views of the drawings.

As conducive to a clearer understanding of certain of the structural features described herein, it should be pointed out that existing connecting devices of the general character described herein are characterized by certain shortcomings. Many of these devices do not include any

2

means for assuring that the safety catch will be moved into the locked position when the cover member is locked down on the clasp. In other clasps, the safety catch has a tendency to open inadvertently, and still another difficulty is the fact that these safety catches are hard to operate. It is an object of the present invention to overcome the above difficulties in a practical manner.

Referring now to the drawings in detail, the center catch or clasp, generally indicated at 10 in Figure 1, includes the sections 11 and 12 constructed in any well-known manner to be secured to the ends 13 and 14 of a watch bracelet or the like. The clasp 10 has a top cover 15 which may be snapped into the locked position to hold the end section or link 12 in locked position. Additionally, there is a safety catch included in the clasp 10 to further lock the parts in position against accidental unlocking, all as will be more fully described hereinafter. As best shown in Figures 5 and 6, the end section 11 is formed into a channel-shaped housing member 16, the cover 15 being pivoted thereto at its free end by way of a pin connected to the upstanding ears 16a and 16b of the housing part 16. The housing part has upstanding longitudinal side walls 16c and 16d and inturned flanges or overhanging portions 16e and 16f at the upper edges of the walls. A pair of oppositely disposed transversely aligned notches 16g and 16h are formed in the walls 16c and 16d of the housing part adjacent its free end.

The notches 16g and 16h are large enough to provide a seat to receive the cross bar 18 forming the front end of the end section 12. End section 12 is also provided with an opening 19 adjacent the cross bar 18 so that the end section 12 may be slipped over the cover 15 when in its open or upper position, as shown in Figure 8. Therefore, if the cover is forced down upon the housing part 16 after the end section 16 has been slipped thereover, the cover will guide the cross bar 18 into the notches 16g and 16h, thereby locking the parts in the position shown in Figures 1 and 6. However, if the cover comes open accidentally, the end section 12 will slip out of the locked position to open the bracelet. Accordingly, a separate locking device or a secondary locking arrangement is important, particularly where the bracelet is expensive, for example, where it is used to support a watch.

A safety catch, generally indicated at 20 (Figures 4 and 6) is slidably mounted in the housing part 16. The catch 20 includes a bar having side walls 20a and 20b fitting against the side walls 16c and 16d of the housing part 16.

Catch bar 20 has an L-shaped projection 20c at one end thereof providing a lug projecting toward the free end of member 16 with its horizontal undersurface 20d spaced sufficiently above the bottom edges of the notches 16g and 16h to allow clearance for the cross bar 18 as shown in Figure 6.

The top side 20e of the catch 20 slants downwardly to provide a cam surface for a purpose to be described hereinafter. Accordingly, the catch may slide in the housing part to a position where it will retain the cross bar 18 of the end section 12 locked within the housing part and, more particularly, in the notches 16g and 16h. The catch may also be slid in the opposite direction to the position shown in Figure 8, where all parts are in the open position for removal of the end section 12.

To move the catch 20 in either direction, there is provided a lever part generally indicated at 21 (Figure 3), pivotally mounted between the side walls 16c and 16d of the housing part by a pin 22 (Figures 5 and 6), extending into the side walls of the housing part. The pin 22 is immediately above the side walls 20a and 20b of the catch and serves to hold the catch in its sliding position within the housing part. A pair of ears 21a and 21b extend toward each other from the main body portion of the lever member and are joined at their extremities in any desired manner to form the operating end 21c of the lever. The ears and end 21c form a lever arm which extends into the opening 20f in the bottom of the catch 20 and through an opening 23 in the bottom of the housing part 16.

As shown in Figure 3, the upper end portion 21d of the lever 21 is rounded so that it forms a tab which may be easily operated with the fingernail. This end 21d fits flush with the in-turned flanges 16e and 16f of the housing member when the parts are in the closed position.

To close the catch, the cover 15 may be brought down from the position shown in Figure 8 to the position shown in Figure 6, during which operation the lever member 21 pivots to move the locking member in a left-hand direction to lock the cross bar until the parts assume the position shown in Figure 6. Of course, the lever member 21 may be moved independently of the cover member if desired.

To open the catch, it is merely necessary to raise the cover 15 to the position shown in Figure 8; the parts may then assume either of the positions of Figures 7 and 8. If one desires to remove the end section 12, the lever 21 may be raised to the position shown in Figure 8. The parts will then remain open for the release or reception of the end section.

The end section 12 may also be inserted when the catch or lock member 20 is in the left-hand or closed position shown in Figure 7. When this is done, the bar 18 engages the cam surface 20e of the catch 20, and further downward movement slides the catch to the unlocked position shown in Figure 8. This may be done with the cover 15 or independently thereof.

It is to be noted that the two locking mechanisms, i. e., the cover member 15 and the catch 20 with associated parts are independent of each other except during a locking operation. More particularly, when the safety catch mechanism is in the locked position with the catch 20 in the position shown in Figures 6 and 7, the position of the cover member or its movement from one position to another cannot move the safety catch.

It is only when the cover is moved to the locked position that it helps lock the safety catch. Unlocking the cover cannot change the position of the safety catch and hence cannot contribute to an accidental unlocking of the clasp.

The structural detail of the cover 15 can best be understood from a consideration of Figures 2, 8 and 9. The cover comprises an outer or top portion 24 and an inner portion 25. The outer portion 24 includes a collar 24a formed at one end thereof and a pair of longitudinal side walls 24b and 24c. The end of the outer portion opposite the collar 24a is bent back upon itself to form a rounded end portion 24d.

The inner portion 25 includes a pair of upstanding ears 25a and 25b formed at one end thereof and a vertically disposed lip 25c at the opposite end thereof. The inner portion 25 fits between the side walls 24b and 24c of the outer portion 24 with the ears 25a and 25b in registry with the collar 24a. The lip 25c extends vertically substantially from the rounded portion 24d. The inner portion 25 is held in position by the extending lugs 24e (Figures 8 and 9), extending inwardly from the side walls 24b and 24c.

The inner portion 25 is resilient so that the lip 25c may snap over the cross bar 16j of the housing part 16. The outer portion may be made from sturdier stock to withstand hard usage. By making the cover 15 in two pieces in the manner described, the various manufacturing processes may be simplified considerably, resulting in greater economy and a far superior construction.

It will thus be seen that I have provided a thoroughly practical clasp construction in which the several objects hereinabove have been successfully carried out.

As many possible embodiments may be made of the above invention and as many changes 40 might be made in the embodiment above set forth, it is to be understood that all matter hereinbefore set forth or shown in the accompanying drawings is to be interpreted as illustrative and not in a limiting sense.

45 What is claimed is:

1. A clasp comprising a channel-shaped member having a bottom and side walls and adapted for attachment at one end to a bracelet or the like, said side walls having aligned notches adjacent the other and free end of said member providing a seat for receiving a link to be clasped, a catch slidable lengthwise in said member comprising a bar slidable on the bottom of said member provided with a lug projecting toward the free end of said member and spaced above the bottom of said seat, said catch being slidable toward said free end of said member to a locking position wherein said lug is engageable over a link seated in said seat and away from said free end of said member to a retracted position clearing the seat for removal of the link, a lever pivoted between the side walls of said member on a pivot located above said sliding bar and comprising an arm extending down from the pivot toward and having a connection with the bar and a fingernail tab above the pivot so angularly related to the arm that when the tab is swung upward from said member the arm moves the catch to retracted position, and when the tab is swung down toward said member the arm moves the catch to locking position, a cover for the open side of said member pivoted at said free end of said member, and means on the cover cooperable with said member for releasably latching the cover in position closing the open side of said mem-

ber and holding down the fingernail tab, said cover, in moving from open to closed position, being adapted to engage the fingernail tab, if up, and swing it downward thereby to move the catch to locking position.

2. A clasp comprising a channel-shaped member having a bottom and side walls and adapted for attachment at one end to a bracelet or the like, said side walls having aligned notches adjacent the other and free end of said member providing a seat for receiving a link to be clasped, a catch slideable lengthwise in said member comprising a bar slideable on the bottom of said member provided with a lug projecting toward the free end of said member and spaced above the bottom of said seat, said catch being slideable toward said free end of said member to a locking position wherein said lug is engageable over a link seated in said seat and away from said free end of said member to a retracted position clearing the seat for removal of the link, a lever pivoted between the side walls of said member on a pivot pin located above and holding down said sliding bar and comprising an arm extending down from the pivot through an opening in the bar and an opening in the bottom of said member and having a fingernail tab above the pivot so angularly related to the arm that when the tab is swung upward from said member the arm moves the catch to retracted position, and when the tab is swung down toward said member the arm moves the catch to locking position, a cover for the open side of said member pivoted at said free end of said member, and means on the cover cooperable with said member for releasably latching the cover in position closing the open side of said member and holding down the fingernail tab, said cover, in moving from open to closed position, being adapted to engage the fingernail tab, if up, and swing it downward thereby to move the catch to locking position.

3. A clasp comprising a channel-shaped member having a bottom and side walls and adapted for attachment at one end to a bracelet or the like, said side walls having aligned notches adjacent the other and free end of said member providing a seat for receiving a link to be clasped and being formed with inturned flanges at their

upper edges toward said one end of said member, a catch slideable lengthwise in said member comprising a bar slideable on the bottom of said member provided with a lug projecting toward the free end of said member and spaced above the bottom of said seat, said catch being slideable toward said free end of said member to a locking position wherein said lug is engageable over a link seated in said seat and away from said free end of said member to a retracted position clearing the seat for removal of the link, a lever pivoted between the side walls of said member on a pivot located above said sliding bar and comprising an arm extending down from the pivot toward and having a connection with the bar and a fingernail tab above the pivot engageable with said flanges and so angularly related to the arm that when the tab is swung upward from said flanges the arm moves the catch to retracted position, and when the tab is swung down against the flanges the arm moves the catch to locking position, a cover for the open side of said member pivoted at said free end of said member, and means on the cover cooperable with said member for releasably latching the cover in position closing the open side of said member and holding down the fingernail tab against said flanges, said cover, in moving from open to closed position, being adapted to engage the fingernail tab, if up, and swing it downward thereby to move the catch to locking position.
